UNITED STATES PATENT OFFICE.

MARTIN CHRISTENSON, OF MINNEAPOLIS, MINNESOTA.

SHOE-POLISHER.

No. 854,407.

Specification of Letters Patent.

Patented May 21, 1907.

Application filed May 25, 1906. Serial No. 318,662.

To all whom it may concern:

Be it known that I, MARTIN CHRISTENSON, a citizen of the United States, residing at Minneapolis, county of Hennepin, and State 5 of Minnesota, have invented certain new and useful Improvements in Shoe-Polishers, of which the following is a specification.

My invention relates to machines for polishing shoes, and its object is to improve the 10 devices shown in my Patent No. 524,414, dated August 14, 1894, to render the mechanism easier of operation and more effective in its work.

My improvements are illustrated in the 15 accompanying drawings, in which—

Figure 1 is a plan view of a shoe-polishing machine containing my improvements; Fig. 2 is a side elevation of the same; Fig. 3 a rear elevation; Fig. 4 is a plan view of the inverted machine; Fig. 5 is an enlarged detail of the gearing shown in the lower portion of Fig. 2; and Fig. 6 is an enlarged detail plan view of the left-hand portion of Fig. 1, with portions broken away.

25 In the drawings 1 and 2, respectively, designate the upright and horizontal members of the frame which supports the operative devices, and 3 a plate covering the frame and providing a suitably shaped foot - rest 4. 30 Four polishing brushes are employed; a brush 5 for the front of the shoe, a brush 6 for the heel, and opposite brushes 7 for the sides.

The brush 5 is suspended from the horizontal portion of a bent arm 8 by a sleeve 9 which is held in place thereon by a set-screw 10, and is thereby rendered adjustable. The vertical portion of the arm is supported in an upright hollow tube 11 by means of a set-screw 12, and is therefore adjustable in vertical direction. The tube 11 is carried on the end of a short horizontal rod 13 which is journaled in a pair of bearings 14, to permit it to be rocked, and it is held from axial 45 movement by a sleeve 15 to which it is fastened by a pin 16, the ends of the sleeve abutting the journal - boxes 14. These parts are mounted on a horizontal supporting-plate 17 that is secured to an upwardly inclined 50 frame-piece 18 projecting forward from the horizontal frame members 2.

The heel brush 6 is carried by a pair of angularly bent rods 19, the upright end portions of which are secured to a plate 20 on the back of the brush. The horizontal lower 55 portions of the rods extend through holes in

a block 21 on the rear end of an operating arm 22, and they are held in place and are adjustable in the block by means of set-screws 23.

60 The side brushes 7 are each supported by a vertically arranged angularly bent rod 24 and an inclined similar rod 25. To the brush back along its rear half is attached a plate 26 from which project horizontally outward 65 three pins, a relatively long middle pin 27 and two shorter side pins 28. To the upper ends of the rods 24 and 25 is attached a plate 29 providing three hollow tubes 30 within which the pins 27 and 28 extend loosely. 70 The ends of the pins 28 bear against coil springs 31, while the pin 27 extends entirely through the middle tube and the plate 29, and has at its end a cotter or stud 32 to limit its movement inward. By this arrangement 75 the force of the springs tends to press the brush inward, while the pin 27 serves as a guide as well as brace, and the cotter limits the extent of the inward movement. The ends of the horizontal portions of the rods 24 80 and 25 are secured to cross heads 33 which are slidable forth and back on pairs of guide-rods 34, and the latter are secured to cross-pieces 2 of the frame work. The pairs of guide-rods converge somewhat toward the 85 rear to conform the brush movements to the shape of the shoe sides.

For operating the brushes simultaneously and in the desired courses the following means are provided. A transverse shaft 35, 90 rocked by the operation of a hand lever 36, is journaled in boxes 37 provided on opposite parts 1. On this shaft is fastened a segment 38 of a bevel gear, which meshes with a like segment 39 formed on one side of a depending sleeve 40. The sleeve is loosely supported on a pendent spindle 41 secured to the under side of the central frame member 2. A washer 42 and nut 43 hold the sleeve in place and allow it to be rotated on the 100 spindle. From the upper portion of the sleeve or hub 40 extends rearward the arm 22, which operates the heel brush, and at right angles to it a pair of arms 44 for operating the side brushes. The arms 22 and 44, together with the hub 40 which supports them, 105 constitute a three - armed lever. At the front side of the hub, opposite the arm 22, is a bevel segment 45, which meshes with a like segment 46 on the end of a rocking shaft 47 110 for operating the toe brush. To the ends of the lateral arms 44 are pivotally connected

rods 48 which in turn are pivoted to the under sides of the cross-heads 33, for the purpose of reciprocating the cross-heads and thereby operating the side brushes. The rock-shaft 5 47 has its inner journal-bearing in a hanger 49 pendent from the central frame piece 2; and its outer journal-bearing is provided by a groove in the under surface of the inclined frame piece 18 and a corresponding groove 10 in the upper surface of the rear end of the extension plate 17. On the outer end of this rock-shaft is secured an outwardly projecting rork 50 for engaging the brush-carrying rod 8 to rock it and thereby operate the toe brush. 15 In operation, the rocking of the shaft 35 by swinging the hand lever to and fro, causes the bevel segments 38 and 39 to partially rotate and reverse the hub 40 and thereby oscillate the arms 22 and 44. Such movements of 20 the arm 22 carry the heel brush back and forth in an arc around the shoe heel; and the like movements of the arms 44 serve to reciprocate the cross-heads 33 on their guide-rods alternately in opposite directions to correspondingly reciprocate the side brushes. 25 And the same rocking movement of the shaft 35 causes the bevel gears 45 and 46 to rock the shaft 47 which, by means of the fork 50, swings the rod 8 and thereby reciprocates the 30 toe brush in an arc across the front portion of the shoe.

The arcs in which the toe and heel brushes are caused to move are made to conform as nearly as practicable to the shapes of the 35 parts of the shoe they are intended to polish, and the brushes are made of correspondingly curved shapes.

Having described my invention, what I claim and desire to secure by Letters Patent 40 is—

1. In a shoe polisher, the combination with a main shaft and means for rocking it, of a

pivoted three-armed lever, bevel gears connecting the shaft and lever for causing the shaft movements to oscillate such lever, a 45 rock-shaft, bevel gears connecting the lever and rock-shaft for causing the lever movements to rock said rock shaft, a set of polishing brushes, and means for communicating the motion of said lever and said rock-shaft 50 to the set of polishing brushes, substantially as set forth.

2. In a shoe polisher, the combination with a main shaft and means for rocking it, of a pivoted three-armed lever, bevel gears connecting the shaft and lever for causing the shaft movements to oscillate such lever, a heel brush carried by the middle lever arm to operate in an arc, a pair of side brushes, guide-rods and cross-heads thereon, means connecting the side brushes and cross-heads, and pivotal connections between the latter and the adjacent lever arms for reciprocating the side brushes, substantially as set forth. 55

3. In a shoe polisher, the combination with a main shaft and means for rocking it, of a pivoted three-armed lever, bevel gears for causing the shaft movements to oscillate such lever, a heel brush carried by the middle lever arm to operate in an arc, a pair of 60 side brushes, guide-rods and cross-heads thereon, brush supports attached to the cross-heads, and tubes and spring-actuated pistons and a guiding device connecting the brushes to their supports, substantially as 70 set forth.

In testimony whereof I have signed my name to this specification in the presence of two subscribing witnesses this 19th day of May, 1906.

MARTIN CHRISTENSON.
